UNITED STATES PATENT OFFICE.

JOHN DANKS AND BENJAMIN BARNES, OF MELBOURNE, VICTORIA,
AUSTRALIA.

TRAM-CAR MOTOR.

SPECIFICATION forming part of Letters Patent No. 320,634, dated June 23, 1885.

Application filed February 7, 1885. (No model.) Patented in Victoria November 11, 1884, No. 3,882.

To all whom it may concern:

Be it known that we, JOHN DANKS, a subject of the Queen of Great Britain, residing at Bourke street, West, in the city of Melbourne and British Colony of Victoria, brass founder, and BENJAMIN BARNES, also a subject of the Queen of Great Britain, residing at Queen's Terrace, South Melbourne, in the said Colony, engineer, have invented new and useful Improvements in Tram-Car Motors, (for which we have obtained a patent in the British Colony of Victoria, No. 3,882, bearing date the 11th day of November, 1884,) of which the following is a specification.

This invention consists, first, in the combination, with a tram-car, of a gas-engine for propelling the same, and receivers or vessels in which a gas or a gaseous mixture—such as gas and air or other gaseous compound—is compressed and stored under pressure, such receiver or vessel forming part of or being carried on the tram-car; and, secondly, of a novel arrangement of friction-gear and levers for conveying motion from the gas-engine to the wheels of the car, and also for effecting the operations of starting, stopping, and reversing the motion of the tram-car without stopping the engine.

Its essential features are, first, the use of a gas-engine placed upon and securely bolted to the framing of the tram-car; second, the storing under pressure, in suitable vessels placed upon or attached to the car, of a sufficient quantity of gas or gaseous compound to keep the engine working during the time required for the car to make one or more trips; third, reducing the pressure of the gas or mixture of air and gas so stored to its initial pressure required for the effective working of the gas-engine by means of a reducing valve or valves; fourth, working the engine during the trip and effecting the stopping, starting, and reversing the motion of the car by an arrangement of friction-gear connected to the driving-axle of the car; and that this our invention may be more clearly understood we will now refer to the annexed drawings, in which—

Figure 1 is a longitudinal section of a tram-car with the gas-engine receiver and pressure-reducing valve applied thereto; and Fig. 2 is

a cross-section of the tram-car on the line *a a* in Fig. 1, looking in the direction of the arrow. Figs. 3, 4, and 5 are a front view, a side view, and a plan view, respectively, of the friction-gear and chain mechanism for conveying motion to the wheels and for controlling the car. Figs. 6 and 7 are further details of said parts, and Fig. 8 shows one form of a pressure-reducing valve.

In these drawings, A is the framing of the tram-car, and B the base-plate of a gas-engine bolted to it.

C are receivers under the seats of the car for storing the compressed gas or mixture of gas and air, although they may be placed in any other convenient place on the car.

D and D' are friction-wheels fixed side by side upon the engine-shaft D², and the larger one of which, D, gears with a similar friction-wheel, E, which, together with a smaller friction-wheel, E', is keyed upon an intermediate shaft, E², upon which the chain-sheave F is keyed, so as to convey the motion to pitch chain-sheave H, keyed to the driving-axle J of the tram-car, through the medium of the chain G, working on said sheaves F and H.

K are links for holding at their proper distance the friction-wheels D D' and E E', and L are links for holding at their proper distance the pitch chain-sheaves F and H.

M are eccentric brasses secured into the ends of the forked lever N, as shown in Fig. 6, for putting in and out of gear the friction-wheels D and E.

P is a hand-lever secured to the intermediate shaft, Q, the ends of which are made eccentric, and work in the bearings formed at the upper end of the arm K' of the link K.

R are links, supported at their upper end on the shaft Q, and at their lower ends they have bearings formed in them to receive the lower shaft, S, on which is keyed the friction-wheel T, which gears with the smaller friction-wheels D' and E'.

The following is the mode of operation for working our tram-car motors: At a station convenient to the line of tram-road gas is taken from the mains of gas companies and forced (by compresses worked by steam or other power) into a fixed receiver, and so

stored under great pressure ready for use. Connected with the receiver are service-pipes provided with suitable valves attached, and on or in any convenient place on the tram-car we 5 place storage-receivers C for holding a quantity of the compressed gas, and by means of india-rubber hose and union connection allow the gas to pass from the larger fixed receiver through the service-pipe to the storage-receivers on the car, and so charge them with gas at the same pressure as that in the larger receiver, where a common self-acting retaining-valve prevents the gas escaping from the small receivers when the connection is broken.

15 We attach to the receivers on the car by any suitable connection one or more reducing-valves of any well-known and suitable form, one well-known construction of such valves being shown at Fig. 8 for allowing the 20 gas to be expanded to its original pressure, as in gas-mains, and when so expanded we use it for working the gas-engine. We then start the engine and allow it to continue working. Then, to put the car in motion, we press 25 down the lever N, which, being attached to eccentric brasses M M, brings the friction-wheels D and E into contact; and when we require to stop the car we raise the lever N, and the friction-wheels D and E are then 30 separated. When in contact, the wheel D gives motion to the wheel E, the intermediate shaft, F², and the pitch chain-sheave F, which latter being connected by the pitch-chain G to the sheave H on the driving-axle 35 J, gives a forward motion to the car. When it is required to run the car the contrary way, we separate the wheels D and E by raising the lever N, and we bring the wheel T on the intermediate shaft, S, into gear with the friction-wheels D' and E' by pressing down the hand-lever P, and so impart a reverse motion to the 40 car-wheels.

The advantages of working tram-cars according to our invention are, first, the small 45 amount of dead-weight required to be moved when compared with the steam-motor and the consequent saving in the wear and tear of the tram-road, as it is not necessary to carry the fuel and water required by a steam-engine; 50 second, the absence of fire and smoke in the street, and the nuisance of coal and coal bunkers, and, further, the services of a fireman are

not required; third, the facility with which the engine and the principal working parts of the machinery may be inclosed and protected 55 from the dust; fourth, the small cost at which the tram-cars may be worked under this system.

What we claim is—

1. The combination, substantially as described, with a street-car provided with seats for passengers, storage-tanks for storing a motive power under pressure, a gas-engine connected with said storage-tanks and mounted on the car, and one of the wheel-axles of said car, of transmitting mechanism for transmitting motion to the wheel-axle, consisting of the friction-wheel D on the engine-shaft, the friction-wheel E on a counter or intermediate shaft, E², the chain-sheave F on said shaft, 70 the chain-sheave H on one of the axles of the car, and the driving-chain G, substantially as and for the purpose specified.

2. The combination, substantially as described, with the axle J of the car A, carrying a chain-sheave, F, the gas-engine mounted on said car, the engine-shaft D², carrying friction-wheel D, the counter-shaft E², carrying friction-wheel E, and chain-sheave H, and the chain G, of the lever N, pivoted on the engine-shaft and carrying said counter-shaft E², said parts being arranged for co-operation, for the purpose specified.

3. The combination, substantially as described, with the axle J of the car A, carrying a chain-sheave, F, the gas-engine mounted on said car, the engine-shaft D², carrying friction-wheels D D', the counter-shaft E², carrying friction-wheels E E', and chain-sheave H, the lever N, fulcrumed on the engine-shaft and carrying the counter-shaft E², and the chain G, of the lever P, shaft Q, secured to an arm of lever N, and with which shaft lever P is connected eccentrically, and the friction-wheel T, supported by links from shaft Q and adapted to be brought in frictional gear with wheel E', said parts being arranged for co-operation, as set forth, for the purpose specified.

JOHN DANKS.
BENJAMIN BARNES.
